MATCH BOOK

Thomas J. McKinnon, Jr., Mission, Tex.

Application July 28, 1936, Serial No. 93,077

1 Claim. (CL 206—29)

This invention appertains to new and useful improvements in the general art of paper receptacles, and more particularly to what is generally known as book matches.

5 The principal object of the present invention is to provide a book match construction in such a manner as to compel the user to close the book before he can scratch the match.

Another important object of the invention is to 10 provide an improved match book which has safety as its greatest factor in that the book must be completely closed before the user can scratch the match thus preventing the remaining matches from becoming ignited.

15 These and various other important objects and advantages of the invention will become apparent to the reader of the following specification.

In the drawings:

Figure 1 represents a perspective view of one 20 form of the present invention.

Figure 2 is a vertical sectional view through the form shown in Figure 1.

Figure 3 represents the sheet blank of the form shown in Figure 1.

25 Figure 4 represents the scratching sheet of the form shown in Figure 1.

Figure 5 is a perspective view of a slightly modified form of the invention.

Figure 6 is a vertical sectional view through 30 the form shown in Figure 5.

Figure 7 is a plan view of the sheet blank of the form shown in Figure 5.

Figure 8 is a perspective view of the scratching sheet of the form shown in Figure 5.

35 Figure 9 represents a third form of the invention.

Referring to the drawings wherein like numerals designate like parts, it can be seen that in Figures 1 to 4, inclusive, numeral 5 represents the 40 match book jacket which has one end portion bent backwardly as at 6 and wired as at 7 to the matches 8. The flap portion 9 in the usual way has its free end closed downwardly between the matches 8 and the backwardly bent portion 6. 45 As shown in Figure 3, the flap 9 is provided with an elongated longitudinally extending slot 10. A small rectangular-shaped sheet 11 of the same material as the flap 9 has a scratching surface thereon registerable with the slot 10. This sheet 50 11 is secured at one end to the inside of the strip 5 by wire fasteners 13 so that the same is a flap on the inside of the flap 9. Thus, it can be seen

that when the flap 9 is in open position and a match is extracted from the match group 8, the match cannot be struck on the surface 12 as the sheet 11 will then readily flex. The flap 9 must be closed so that the matches 8 will act as a backing for the sheet 11 and the match can be extended through the slot 10 and struck against the scratching surface 12.

A modified form of the invention is shown in Figure 5, wherein the flap 9a is provided with a transversely extending slot 10a opening through one longitudinal edge of the flap 9a. The supplemental flap 11a is secured at one end to the inside of the flap 9a by a wire fastener 13a. The flap 11a has a transversely extending scratching surface 12a which is registerable with the slot 10a. Obviously, in this form of the invention the flap 9a must also be closed so that the flap 11a can have a firm backing against the match group 8a.

The final form of the invention shown in Figure 9 consists of the strip 5' bent to provide the flap 9' which has the transversely extending slot 10' therein. The flap 9' is substantially longer than the flap 9 or 9a and the extended portion is bent inwardly to provide the supplemental flap 11' which has the striking surface 12' thereon only registerable with the opening 10' when the flap 11' is disposed firmly against the match group 8'.

While the foregoing specification sets forth the invention in specific terms, it is to be understood that numerous changes in the shape, size, and materials may be resorted to without departing from the spirit and scope of the invention claimed hereinafter.

Having described the invention, what is claimed as new is:

A match book of the character described comprising an elongated strip of material, a match group, one end of the strip being bent backwardly and secured to the match group, the other end of the strip being bent backwardly to provide a cover flap, said cover flap being provided with a slot therein, an internal flap having a striking surface thereon registerable with the slot when the internal flap is pressed against the match group, said internal flap consisting of an extension of the cover flap bent backwardly against the inside of the cover flap.

THOMAS J. MCKINNON, JR. 50
